PORTABLE ELEVATOR

Robert J. Owen, Chatham, Ontario, Canada

Application April 27, 1938, Serial No. 204,640

3 Claims. (Cl. 198—115)

The present invention relates to portable elevators for grain, sand, gravel or other finely divided or granular material, being particularly useful for handling grain in loading or unloading 5 wagons or trucks and for transferring grain from such wagons or trucks to railroad cars.

Among the objects of this invention is an elevator which shall be relatively small and easily attached to and transported by the ordinary 10 grain wagon or truck.

Another object is a device of the kind indicated which may be folded to decrease the space occupied.

Another object is means whereby the conveyor 15 belt may be adjusted in length to permit such folding and to permit adjustment for operation.

Still other objects and advantages will be apparent to those skilled in the art upon reference to the following description and the accompanying 20 drawing in which

Figure 1 is a side elevation (from the left of Figure 2) showing the mounting of the device on a truck and showing in dotted lines the folded or transport position.

Figure 2 is an end elevation of the truck and elevator.

Figure 3 is a partial elevation of the elevator from the truck side.

Figures 4 and 5 are respectively sections on lines 30 4—4 and 5—5 of Figure 3.

Figure 6 is a partial elevation with parts in section showing the rack joint.

As indicated in the drawing, the device is of a conventional type of elevator, i. e., it comprises 35 a continuous belt, having affixed buckets or cups, passing over suitable pulleys in the top and bottom of the structure, but is novel in certain particulars.

As shown, the elevator may be mounted upon 40 a suitable truck 10, a platform 11 and stay 12 being provided for support. The lower part 15 of the elevator preferably extends through the platform 11 and constitutes the hopper or receiver for the material to be handled. When unloading 45 the truck, a suitable chute 16, leading from the truck body to the receiver 15 is preferably used.

From the receiver 15, two hollow legs 18 extend upwardly to a point at substantially the upper edge of or a short distance above the truck 50 body and into the lower portions of a pair of sleeves 19, which are fixed to the stays 12.

The sleeves 19 extend for a short way, above the ends of legs 18, the length being determined by the desired amount of adjustability of the upper 55 part. Further, these sleeves 19 are each in

two parts hinged together as indicated at 20 in Figure 3, with the hinge lines substantially flush with the upper ends of legs 18.

Leg continuations 18a are of the same size as legs 18 and are slidably fitted into the upper portions 19a of sleeves 19. These continuations extend the length of the legs to the desired height and at their upper ends open into the elevator head 25, the latter having therein the drive pulley or sprocket (not shown) over which runs the conveyor belt 26, and also has connected thereto the delivery chute 27 leading to the intended receptacle (such as a railway car).

The conveyor belt may be driven in any suitable fashion but is shown as having a drive pulley 30, secured in driving relation to the upper conveyor pulley or sprocket, and driven, for example, by a belt 31 from a small internal combustion engine 32 mounted on platform 11. Since such an elevation would necessarily extend to too great a height to be practicable for permanent attachment to a truck because of the overhead clearance of small bridges and the like, and because of necessary bracing, the present device is arranged to be folded as indicated in the dotted 25 line position of Figure 1.

In order to be able to fold the elevator the sleeves 19 connecting the two leg portions 18 and 18a are hinged as shown and means is also provided for moving upwardly the upper parts of the legs 18a in order to put sufficient tension on the conveyor 26. This means consists of a rack 35 operating in a suitable guide 36 and movable by a gear 37 keyed to shaft 38 carried in bearings 39 mounted upon legs 18. This shaft 38 terminates at one end in a suitable crank 40 and carries also a ratchet wheel 41 engaged by a pawl 42 serving to fix the gear against turning. The rack 35 cooperates at its upper end with a U-shaped bar 45 fixed to the portions 18a of the legs, being provided with a flat portion at the bottom against which the top of the rack acts so that movement of the rack through operation of crank 40 extends or allows shortening of the legs.

Suitable means such as the hook 50 may be used to assure the maintenance of the device in erected position.

As indicated, the device is intended to be permanently installed upon a suitable truck and utilized for the quick unloading of the latter, being erected and folded as required for use or transportation. After use, it is necessary merely to loosen the conveyor belt by lowering the upper 55

portion and then, after disengaging hook 50, lower to the dotted line position of Figure 1.

While engine 32 has been shown as the power supply for operation of the elevator, it is obvious that any other motive power could be used.

Now having described the invention, and the preferred embodiment thereof, it is to be understood that said invention is to be limited, not to the specific details herein set forth, but only by 10 the scope of the claims which follow.

What I claim is:

1. An elevator of the endless belt and bucket type, having hollow legs within which said belt operates, said legs being divided horizontally, 15 sleeves loosely surrounding said legs at the point of division and hinged together, and means for moving said leg portions relatively in said sleeves, whereby to adjust the tension on said belt and permit the sleeves and leg portions to be folded.
- 20 2. An elevator of the endless belt and bucket type, having hollow legs within which said belt operates, said legs being divided horizontally,

sleeves loosely surrounding said legs at the point of division and hinged together, and means for moving said leg portions relatively in said sleeves, whereby to adjust the tension on said belt and permit the sleeves and leg portions to be folded, 5 said means comprising a rack fixed to one of the leg portions and a cooperating gear carried by the other leg portion and means for operating said gear.

3. An elevator having hollow legs housing an 10 endless bucket conveyor, each of said legs being made of end to end sections and having a sleeve closely fitting around and fixed to one of the adjacent ends of said sections, said sleeve being likewise in sections hinged together, whereby said 15 leg and sleeve may be folded, and means for moving one of said leg sections relatively in said sleeve and consisting of a rack and pinion carried by one of said sections, said rack having an extension fixed to the other of said sections. 20

ROBERT J. OWEN.
